SEA STOP

Jesse D. Langdon, Downey, Calif.

Application January 9, 1942, Serial No. 426,148

3 Claims. (Cl. 114—68)

1

The present invention relates to protective devices for vessels, such as boats and ships, and aims to maintain same afloat after the hull has been perforated by accident or otherwise.

The primary object of the invention is to stop the entry of water into the hull of a marine vessel, in the event the hull of same has been perforated, by providing an inflatable bag or balloon combined with means capable of inflating and expanding the bag or balloon to the extent necessary to fill any compartment within the hull of the vessel to maintain same afloat.

Another object of the invention is to stop the entry of sea water into the hold of a ship after the hull has been penetrated by accident or explosion by bomb, shell or torpedo by the provision of an armored or protective casing for an inflatable bag or balloon, either separate or built into the bulkhead or compartments of a vessel.

A further object of the invention is to provide a portable protected balloon attached to a source of air or other suitable fluid and which can be placed within a leaking ship or attached to a bulkhead compartment and which is capable of being inflated to force water out of said compartment to restore and maintain the buoyancy of the ship.

A still further object is to provide nesting means for inflatable bags or balloons located at various points within the hull of a vessel, said bags or balloons capable of being expanded and released by the force of concussion and subsequently inflated and automatically expanded thereby to force water from within the hull of a ship and restore and then maintain the buoyancy of the vessel to hold same afloat until repairs can be made.

Another object is to provide automatic valve means in combination with suitable bags or balloons, whereby the force of pressure, concussion or the action of moisture will operate the valve and permit the release of air, gas or other suitable fluid from the container into said bags or balloons to inflate same.

Another object is to provide a container for a fire smothering gas.

Still another object is the provision of a suitable protective housing or casing to install or store the sea stop comprising the invention.

The accompanying drawings are for the purpose of illustration only and the present reduction to practice may be changed within the scope of the claims.

In the drawings:

Fig. 1 represents a fragmentary portion of a

2

ship's hull, partly cut away in section showing compartments, bulkheads, and decks, and sea stop containers;

Fig. 2 is the same as Fig. 1 with bags partly inflated in punctured compartments;

Fig. 3 shows a sectional view of a sea stop container provided with a sea stop bag, a conduit, an automatic valve and a compressed air container housed therein;

Fig. 4 is a vertical section of the complete assembly comprising an automatic valve;

Fig. 5 is a vertical section of a central fragmentary portion of a valve showing a sealing disc perforated by a point due to distortion inwardly of the diaphragm;

Fig. 6 is a vertical section of a valve showing a sealing disc shown perforated by a point by expansion of an element; and

Fig. 7 is a vertical section of central fragmentary portion of a valve provided with a diaphragm bulged away from a cap by fluid pressure escaping through a perforated disc and a valve recharging stem.

The structural parts comprising the mechanical organization of the invention and the operation thereof are as follows:

The casing designated 1 may be made of metal or of rubber, or of flexible fabric; the casing is provided with a protective hollow cover 1c, of suitable material, which normally rests freely upon its bottom plate, and as appears from Fig. 3, in particular, is capable of being raised by the bag or balloon 2 being inflated. The conduit 3 connected to the automatic valve 4 is attached to the tank 5 which contains a compressed fluid such as air or gas, including fire smothering gas. As appears from Fig. 3, the protective cover 1c is provided with a plurality of perforations 1p, two being illustrated, which are disposed adjacent the periphery of the front face of the casing 1, to afford communication with the interior of the casing 1 and the outer atmosphere.

The automatic valve 4 comprises a laminated diaphragm 6 composed of a relatively thin perforated plate 6a preferably made of material capable of flexing by impact, concussion or pressure thereagainst, and returning to normal position after pressure is released, another disc 6b lies adjacent to disc 6a made of material subject to rapid expansion when contacted by moisture such as suitable woods or compressed cotton for example; a third disc 6c made of relatively stiff and impervious material including suitable plastics, such as hard rubber, or of thin metal.

The disc 6a is stiffer than discs 6b and 6c com-

bined so as to provide sufficient resistance to support discs 6b and 6c against the impact of the base 8b of perforating point 8 which is provided with a shoulder 8s resting on disc segments 6a, 6b, and 6c which form the laminated diaphragm 6 which is centrally perforated to receive the threaded, shouldered shank 8s of the point 8 extended therethrough.

Diaphragm 6 is supported at its periphery by the inturned flange of ring 9 which is internally threaded to receive cap 10. Cap 10 is provided with coupling neck 10n having a sealing disc 7 made preferably of lead or some soft material subject to being easily perforated or melted at low heat. A coupling nut 11 surrounding the flange of connection 5c of container 5 holds sealing disc 7 between the ends of neck 10n and flange of connection 5c, thus sealing the compressed air or gas in the container 5. The flanged shank of point 8 has a T-shaped passageway 8T; the transverse portion of the T disposed within a chamber 12 formed between the inside of cap 10 and diaphragm 6. The longitudinal portion of passageway 8T forms a passage through the flanged shank 8s of point 8.

The shank 8s is threaded at its lower end and serves as a coupling element as well as a conduit communicating between chamber 12 and conduit 3 which is coupled to shank 8s by nut 13.

Conduit 3 is in turn attached to bag 2 which is inflated by either impact or concussion or pressure or the expansive action of moisture against the external side of diaphragm 6c causing point 8 to perforate sealing disc 7 which is immediately withdrawn from the perforation in disc by the action of pressure fluid escaping into chamber 12 and exerting pressure against the internal side of diaphragm 6 to further open valve 4 as per Fig. 7.

The pressure fluid, air or fire smothering gas now passes into and inflates bag or bags 2 located in any of the compartments C supplying sufficient buoyancy to hold a vessel afloat indefinitely.

In case pressure or impact fails to operate the valve 4 moisture entering the chambers C viz. through the stated perforations 1p will contact and swell segment 6b of diaphragm 6 and per Fig. 6 and cause point 8 to puncture sealing disc, thus inflating bags or balloons 2. Similarly, in the circumstance of an explosion, the stated perforations 1p afford communication with the interior of the casing 1, whereby the resulting concussions flex the diaphragm 6, as indicated in Fig. 5.

In case fire smothering gas is used in container 5 and disc 7 is melted away by heat, the gas will aid in controlling fire in case bag 2 is destroyed. By having casing units 1 placed at various points in each compartment, a fire having destroyed some of the bags 2 might be extinguished after which water entering a compartment C would cause the release of other valves, thus inflating other bags which would then act to float the ship. Some units could be provided with fire proof cas-

ing 1 of fire proof material and valves with disc 1 not designed to melt at low temperature, thus only pressure or moisture would cause the valves to operate and function to fill bags 2 and refloat a ship already partly or on the brink of being sunk. If desired, the bags 2 could be made of fireproof material.

Having described my invention and the structure and operation thereof, I claim:

1. For use with a device of the kind described, a valve construction comprising a hollow body having a valve element closing an inlet port disposed thru one side of the hollow body, a valve opening member projecting against the closure element and supported by a diaphragm element disposed opposite the port, another diaphragm member made of material expansible by contact with moisture and being held and assembled by and between the first named diaphragm and an outer perforated diaphragm member forming a composite laminated flexible diaphragm closing the hollow body opposite to the port and being capable of flexing under external pressure to open the port closure, also being affected by moisture contacting the expansible member supported by the perforated member to urge the first named diaphragm against the valve opening member to open said port.

2. In a device of the character described, the combinational structure comprising a casing; an inflatable bag enclosed in said casing; a cover for the casing arranged to be displaced by said inflatable bag relative to said casing, said cover being perforated; tank means for containing gas under pressure; conduit means interconnecting said inflatable bag and said tank means; and valve means controlling the flow of gas from said tank means to the interior of said inflatable bag; said valve means including a hollow body having a side formed of material arranged to be displaced in the presence of water, said valve means further comprising a pointed element supported by said water-displaceable side, said valve means further comprising an element normally obstructing communication of said conduit means with the interior of said tank means, said element being disposed within the range of movement of said pointed element, whereby under the condition of presence of water exteriorly of said casing means and flowing through said perforations, such pointed element is actuated by said water displaceable side of the valve body, thereby puncturing said normally obstructing element and releasing the compressed gas from said tank means, and thus inflating said bag.

3. A device of the character defined by claim 2 wherein the gas under pressure within the tank means is a fire extinguishing gas and the element normally obstructing said conduit is fusible under elevated temperature.

JESSE R. LANGDON.
